UNITED STATES PATENT OFFICE.

THOMAS ELLWOOD BUCKMAN, OF JACKSONVILLE, FLORIDA.

CAR-COUPING.

SPECIFICATION forming part of Letters Patent No. 298,445, dated May 13, 1884.

Application filed September 17, 1883. (No model.)

To all whom it may concern:

Be it known that I, THOMAS E. BUCKMAN, of Jacksonville, in the county of Duval and State of Florida, have invented a new and Improved Car-Coupling, of which the following is a full, clear, and exact description.

The object of the invention is to improve car-couplings, as hereinafter described, and pointed out in the claims.

Reference is to be had to the accompanying drawings, forming part of this specification, in which similar letters of reference indicate corresponding parts in all the figures.

Figure 1 is a longitudinal sectional elevation of my improved car-coupling, showing a link held therein. Fig. 2 is a sectional plan view of the same. Fig. 3 is a longitudinal elevation of the same, showing it uncoupled, and also showing the cam as when turned up to raise the locking-block. Fig. 4 is a cross-sectional elevation of the same on the line $x-x$, Fig. 2. Fig. 5 is a like section, showing the pawls under the locking-block. Fig. 6 is a detail view of the pendulum-pawl.

The draw-head A, which has a longitudinal slot, A', or opening in its bottom at the outer end, is held to slide between two guide-plates, B, secured to the car-bottom. The draw-head is provided on its bottom with an apertured lug, C, through which a rod, D, passes, which is surrounded by a compression spiral spring, E, which presses the draw-head toward the end of the car. A coupling-hook pin, F, provided at its free end with an upwardly-projecting prong, F', is pivoted in the draw-head, and is adapted to swing in the slot A'. The under side of the top of the draw-head is provided with a recess, F'', for receiving the upper end of the prong F'. A rocking shaft, G, at right angles to the draw-head, is journaled in the side plates, B, and extends to the side of the car, where it is also suitably journaled, and passes through longitudinal slots H in the draw-head. The shaft G is provided at its outer end with a handle-lever, G', which is locked in place by a pendulum-pawl, J, pivoted to the side of the car. A cam projection, K, is formed within the draw-head on the shaft G. A flat block, L, is provided with a spindle, M, at its rear end, which spindle is sur-

rounded by a spiral spring, N, held between a collar, O, formed at the inner end of the block L, and a collar, P, through which the spindle M passes loosely. The collar P is provided with laterally-projecting pivots a, which pass 55 through longitudinal slots d in the sides of the draw-head, and into longitudinal slots g in the inner sides of the plates B. Pawls Q are held in recesses R in the inner surfaces of the plates B, and are provided at the upper ends 60 with flanges Q', which project into and through the slots H. The flanges Q' are beveled at their front and rear ends. The plates B are united at the outer ends and at the bottom edges with a cross-plate, S, upon which the draw-head 65 rests. The rear end of the draw-head is provided with an aperture, T, having rounded edges, to permit of the inclination of the spindle M, which passes through it. The top and bottom of the draw-head are open, except at 70 the front end.

The operation is as follows: If the draw-heads come together, the link U enters the draw-head A, and when the end of the said draw-head is struck by the opposite draw-head, the draw-head A will be pushed in the inverse direction of the arrow a' and the front edge of the plate S swings the coupling-hook pin F upward and through the link U, whereby the cars are coupled automatically. At the 80 same time the front ends of the slots d strike the pivots a and move the collar P, the spindle M, and the block L in the inverse direction of the arrow a', and the block L drops and catches behind the shaft G and prevents the spring E 85 from pushing the draw-head in the direction of the arrow a', and securely locking the coupling. If the cars are to be uncoupled, the handle-lever G' is swung into the vertical position, and is then thrown down again and is locked 90 automatically by the pendent pawl J. By swinging the lever G' upward, the shaft G is turned in such a manner that the cam K passes under the free end of the block L and moves the same upward, so that it can slide over the 95 shaft G, and the spring E can then push the draw-head in the direction of the arrow a', and the coupling-hook pin can move beyond the plate S, so that it can drop, whereby the cars will be uncoupled. As soon as the block L is 100

swung upward, the pawls Q swing toward each other and under the block L, which is supported by the flanges Q', until, by the separation of the cars, the draw-head is free to be projected by the spring N, and the collar O strikes the rear beveled parts of the flanges Q' and pushes the pawls Q into the recesses R again. When it (the draw-head) is pushed inward in the inverse direction of the arrow a', the collar O strikes the forward beveled parts of the flanges Q', and pushes the pawls Q back into the recesses R, to permit the block L to drop. The spring N presses the end of the block L toward the shaft G, a cross-pin, n, in the end 5 of the spindle M preventing the said spring from pressing the block L too far in the above-mentioned direction. The spring N is the ordinary buffer-spring used on cars.

Having thus fully described my invention, I claim as new and desire to secure by Letters Patent—

1. In a car-coupling, the combination of the draw-head A, rear apertured at T, and having slots d H, the sides B B, having flanges Q', inner recesses, R, and slots g, the shaft G, having outer arm, G', and cam K, the block L, having a rear spindle, M, collar O, and spring N, the journaled collar P, and the pawls Q, as and for the purpose described.
2. The combination, with a rod, D, surrounded by a spiral spring, E, and placed below the draw-head, of the apertured lug C, arranged on the bottom of the draw-head, as and for the purpose specified.
3. The combination, with a sliding draw-head, A, of the upwardly-swinging hook F, the shaft G, provided with a cam projection, K, the swinging locking-block L, the pawls Q, the spring E, and the cross-plate S, substantially as herein shown and described.

4. The combination, with the sliding draw-head A, of the upwardly-swinging hook F, the shaft G, provided with a cam projection, K, the block L, having a spindle, M, the collars O and P, of which the latter is provided 45 with pivots a, the spring N, the spring E, and the cross-plate S, substantially as herein shown and described.

5. The combination, with the sliding draw-head A, of the upwardly-swinging hook F, 50 the shaft G, having a cam projection, K, the block L, the spindle M, the spring N, the pawls Q, held in recesses R in the plates B at the sides of the draw-head, the cross-plate S, and the spring E, substantially as herein shown and 55 described.

6. The combination, with the pivoted hook-coupler F, and bottom S, having slot A', of the draw-head A, projecting beyond the hook and having in the top a recess, F, to receive 60 the hook-point, as shown and described.

7. The combination, with the sliding draw-head A, having slots H, of the side plates, B, having recesses R, the pawls Q, held in the recesses, the swinging hook F, the shaft G, provided with a cam projection, K, and a swinging block for locking the sliding draw-head in place, substantially as herein shown and described.

8. The combination, with a sliding draw-head, of an upwardly-swinging hook pivoted in the same, the shaft G, a swinging locking-block adapted to catch on the shaft and lock the draw-head in place, the handle-lever G', and the pendulum-pawl J, substantially as 75 herein shown and described.

THOMAS ELLWOOD BUCKMAN.
